UNITED STATES PATENT OFFICE.

ISAAC N. BUCK, OF ELGIN, ILLINOIS.

TUBULAR LANTERN.

SPECIFICATION forming part of Letters Patent No. 359,708, dated March 22, 1887.

Application filed October 4, 1886. Serial No. 215,277. (No model.)

To all whom it may concern:

Be it known that I, ISAAC N. BUCK, of Elgin, in the county of Kane and State of Illinois, have invented certain new and useful improvements in Lanterns; and I do hereby declare that the following specification, taken in connection with the drawings furnished and forming a part of the same, is a clear, true, and complete description of the several features of my invention.

My said improvements are specially applicable to what are known as "tubular-frame lanterns," and my main objects are to secure durability of the movable parts and to simplify construction, with corresponding economy in manufacture, and also to provide for special convenience in the adjustment and control of the globe for lighting and trimming.

After describing the constructions illustrated in the drawings, the features deemed novel will be specified in the several clauses of the claim hereunto annexed.

Referring to the drawings, Figure 1 is a front view of one of my lanterns in a desirable form as adjusted for use. Fig. 2 is a similar view with the globe and its base-plate raised and held as for lighting or trimming. Fig. 3 is a side view of the same with the globe cap or hood raised, and with the globe tilted as for its removal. Fig. 4 is a lateral vertical section of the globe cap or hood and the central pendent portion of the tubular frame. Fig. 5 is a view of the globe base-plate detached from its guiding-posts. Fig. 6 illustrates the spring-catch detached from the lantern. Fig. 7 in two views illustrates one of the guiding-posts and its foot-plate detached from the lantern. Fig. 8 is a sectional view of the globe-cap and the central pendent tubular portion of the frame unobstructed by the spring. Fig. 9 illustrates the metal blank from which my globe-hood neck is formed. Fig. 10 illustrates the lower portion of my lantern with its guiding-posts constructed and arranged to operate also as spring-catches.

The lamp-base A and tubular frame B are as heretofore, with the exception that the vertical side tubes, a, are not disfigured by the presence of guides, whether soldered thereon or loosely embracing them, and the lateral top tube, b, is free from any applied attachments,

except such as are requisite for properly securing thereto the usual bail-handle, c. The lateral tubes d, at the base of the frame, have each thereon a vertical guiding-post, e, preferably composed of hard stiff wire. For properly securing these posts, I prefer to provide each post with a head, e', at its foot, and with a foot-plate, e'', having a hole formed by punching and drawing the metal centrally into a tubular form, as illustrated in Fig. 7, so that on passing the top of a post through said hole the head e' will snugly occupy a seat in the under side of the foot-plate and enable a perfect union of the post and plate by the use of but little solder, none of which need be exposed. The foot-plate being struck up to form, so as to be accurately seated on a frame-tube, d, is then neatly soldered to the tube, thus affording a thoroughly reliable union of these posts and frame at little cost, and without impairing the desirably neat appearance of the frame. In cheaper forms of lantern each post e may be inserted in a hole in the piece of metal of which the part d of the lantern-frame is made, and securely soldered therein prior to or after the bending of the metal into tubular form, or the post may be directly soldered upon the top of the tube.

The central pendent tubular portion, f, of the frame at its top is as heretofore, with perhaps the exception of a few minor features incident to the use of the interior spiral spring, g, which has a suitable abutment at its upper end within the tube. It is not essential that the spring g be located within the frame-tube f; but when it is so located the tube is vertically slotted at opposite sides for the reception of a cross-wire, or in lieu thereof two short wires, h, on the hood or globe-cap C, or on its neck i, so that said spring at its lower end may bear upon said wires, and through them force the globe-cap downward upon the top of the globe D. Any of the well-known forms of spring or wire collar may be employed as a globe-collar, K, on the under side of the globe-cap; but the simple well-known form shown is found to be fully reliable.

The tubular neck i on the globe hood or cap is novel, in that it is provided with integral finger-pieces i', thus obviating the use of such separate wires or strips as have heretofore been

soldered to the neck or the hood, or to both. As indicated in Fig. 9, I provide a blank of sheet metal, which, when bent into tubular form, affords material for the integral finger-pieces *i*', which are in turn developed by bending portions of the metal outward and downward, as clearly shown. I prefer to have two finger-pieces; but one can be thus provided for without departure from this portion of my invention, by means of which a specially neat and finished appearance is secured and a strong and durable cap-lifting device afforded at low cost.

The globe base-plate *E* may or may not integrally include the usual perforated plate, *l*, but it should afford an annular seat for the globe, and have the guiding-eyes *m*, one on each side, and each adapted to loosely embrace a guiding-post, *e*.

At one side of one of the posts *e* there is a spring-catch, *n*, secured to the tubular frame at its foot and extending upward, so that its upper end bears firmly against the post at the height to which the base-plate should be lifted for lighting or trimming, and the top of the spring is bent so that it partially embraces the post laterally; but it is provided with inclined edges, so that the base-plate eye when moved upwardly will laterally displace the top of the spring and allow the latter to then spring back beneath the eye and operate as a supporting-catch for the base-plate in maintaining it in its elevated position. The opposite post may have a similar catch; but I find that one can be safely relied upon. For lowering the globe and base-plate, the spring-catch is pressed outwardly from its supporting-contact with the ear *m*.

While I prefer the catch as shown, I do not restrict myself to a separately-constructed catch, because good results will accrue if it be dispensed with as a separate or distinct element, provided the posts *e* be made to perform the double function of guides and spring-catches, as illustrated in Fig. 10. I have stated that said posts should be composed of hard stiff wire, and if the metal be properly selected as to resiliency the posts will also serve as springs, so that when they are provided with the catch-seats *e*', and slightly inclined outwardly at their upper ends, they will be forced slightly toward the globe by the ears *m* of the base-plate when the latter is lifted, and when said ears occupy said catch-seats the posts will promptly spring outwardly, and thus firmly maintain the globe and plate in their elevated position. For lowering the globe and base-plate, the two posts would be pressed toward each other. It is not essential that both posts serve as springs, it being obvious that one can be relied upon for good service.

The partial obstruction of the interior of the pendent tubular portion *f* of the frame by

the hood-spring and cross-wires is by some people deemed objectionable; and hence I sometimes arrange the spring as shown in Fig. 8, wherein the tubular portion *f* is shown to be provided with an exterior projecting seat, *f*', for the upper end of the spring *g*, which in this instance loosely surrounds the pendent frame-tube. The hood or globe-cap *C* has a central hole, which is quite fully occupied by the frame-tube *f*, so that the upper annular surface of said hood next to the tube 75 can serve as a seat for the lower end of the spring. The tubular neck *i* is sufficiently larger than the frame-tube *f* to afford an annular space ample for the free reception of the spring. In assembling these parts, the spring 80 is first placed on the frame-tube, the hood and its neck then applied, and the spring temporarily compressed, and then the lower end of the frame-tube is abruptly expanded, so as to securely lock the three parts together. In 85 order that this expansion of the frame-tube should be restricted to the lower end thereof, it is advisable that the metal be longitudinally slotted at intervals around the edge, to enable the metal to be abruptly bent outwardly, 90 thus affording a good bearing for the coincident surface of the under side of the hood.

With the globe-hood coupled to the frame, as last described, it will be seen that the main frame having been constructed, the globe-hood can be attached without soldering, and the base-plate also readily applied, thus reducing the cost of assembling to a minimum. It will also be seen that the lantern is strong and durable and contains no superfluous metal, 95 and that it can be cheaply constructed.

Having thus described my invention, I claim as new and desire to secure by Letters Patent—

1. In a tubular-frame lantern, the combination, with the tubular frame and a globe hood or cap forced downwardly by a spring, of a base-plate for a globe disconnected from said hood, but forced into and held in its normal position by the hood-spring acting upon an intervening globe, vertical posts projecting upwardly from horizontal lower portions of the tubular frame, guide-eyes on the base-plate for loosely embracing said posts, and a spring-catch for maintaining said plate in an elevated position on said posts, substantially as 115 described.

2. In a tubular-frame lantern, the combination, with the central pendent tubular portion of the frame and a spring, of a globe hood or cap having a tubular neck surrounding said pendent portion of the frame and provided with a thumb-piece integral with the metal of which said neck is composed, substantially as 120 described.

ISAAC N. BUCK.
